LAMP FIXTURE FOR BEDS AND THE LIKE

Filed Feb. 23, 1921

Patented July 24, 1923.

1,462,498

UNITED STATES PATENT OFFICE.

LOUIS ROTH, OF NEW YORK, N. Y., ASSIGNOR TO CHARLES F. KINSMAN, OF NEW YORK, N. Y.

LAMP FIXTURE FOR BEDS AND THE LIKE.

Application filed February 23, 1921. Serial No. 447,284.

To all whom it may concern:

Be it known that I, LOUIS ROTH, a subject of Austria-Hungary, residing at the city of New York, county of Bronx and State of New York, have invented a certain new and useful Lamp Fixture for Beds and the like, of which the following is a specification.

This invention is a fixture whereby a lamp, mirror, or other appropriate article may be attached securely to a bedstead, dresser, or other article of furniture.

Although the fixture of my invention is useful in attaching articles generally to objects of furniture and in other places, the invention is designed for use, more particularly, as a means for maintaining an incandescent lamp and its encasing hood in a fixed position upon a bedstead so as to occupy a position thereon for supplying a light for reading purposes.

In this connection it is well known that there exists a wide variety of bedsteads some styles of which are composed of wood with more or less ornate headboards, whereas other styles of bedsteads are composed of metal the top rails of which differ in cross section.

The fixture as I have constructed it is useful for the attachment of a lamp and hood to any variety of bedstead, and, moreover, it is simple and economical of construction, easily attached, and is efficient in fixedly supporting the article in a permanent relation to the bedstead.

The invention in a practical form includes a stem, a head in fixed relation to the stem, said head being provided with a curved face the radius of which corresponds to the cross section of the bed rail, a demountable collar one face of which is curved correspondingly to the face of the head and the opposite face of which is a plane surface, a compressible washer in contact with the plane surface of the collar, and means for clamping the stem and head in fixed relation to a bedrail.

The head constitutes a member to which the lamp hood, or other article, is rigidly attached. With this head co-operates the collar and the washer when the fixture is fitted to a bedrail the surface of which is flat, whereby the operation of tightening the clamping nut on the stem applies pressure for the compression of the washer, the

several parts co-operating to so firmly mount the lamp in position that for all practical purposes said lamp is immovable; but when it is desired to mount the fixture on a bedrail of circular cross section, the washer and the collar are removed from the stem, and the latter is fitted in an opening in the circular bedrail so that the curved face of said head is in direct contact with the bedrail, the several parts being firmly clamped by tightening the nut on the stem.

Other functions and advantages of the invention will appear from the following description taken in connection with the drawings, wherein—

Figure 1 is an elevation of my fixture applied to the headboard of a wooden bedstead.

Figure 2 is a similar view of the fixture in an operative position on a cross sectionally circular rail of a metal bedstead.

Figure 3 is a longitudinal sectional elevation through the fixture disconnected from the bedstead and independent of the article to be supported.

The fixture of my invention comprises a head member A, a stem B, a collar C, and a washer D, the preferred constructions of which are shown more particularly and in detail by Figure 3 and the mode of using which parts is exemplified in Figures 1 and 2.

The head member A is a single piece of metal provided with a curved face a, the radius of which conforms substantially to the surface of the cross sectionally circular object H' to which the fixture is to be applied as illustrated in Figure 2. As shown, the head A is a separate piece of metal from the stem B, and to make provision for the attachment of the stem and the head, the latter is provided with a tapped socket b, into which is screwed the male threaded end portion b' of said stem, although the parts A B may be composed of one piece if desired or said parts may be coupled by means other than the threaded joint shown.

For the attachment of the lamp hood E shown as a cross sectionally curved element, the head or member A is provided with a curved face e, against which the hood is fitted so as to provide for the reception of a screw e'. Obviously, a mirror or other article to be supported may be substituted for the lamp housing, and said other object may

if desired be secured fixedly in position on the member A by means other than the screw e' .

An incandescent lamp, indicated by dotted lines at F, is coupled as usual with a socket, not shown, the flow of current to said lamp being controlled by the customary pull switch f . Said stem B is provided with a male thread b^2 on which is screwed a nut 10 G adapted to be tightened against a washer g whereby the fixture may be clamped against the element H or H' of a bedstead, or other object.

Collar C is composed of metal centrally perforated to slip over the stem B, it being essential in this invention that said collar be provided with a curved face c and a plane face c' . The curvature of the face c corresponds to the face a of the head in order that the collar may have a solid bearing against the head, whereby the collar is made available for leveling up the head so as to adapt the fixture for service on plane surfaced bed-elements such as H in Figure 1.

Washer D is composed of rubber, leather, or other compressible material, and it is centrally perforated to fit upon the stem, said washer being interposed between the collar C and the bed element H. The washer is shown as having transverse apertures d presenting air pockets, and when the nut G is screwed home the stem and the head act to compress the washer between the collar C and the bed-element H, whereby the frictional contact of the washer with the collar and the bed-element, aided probably to some extent by the air confined within the pockets d, retains the head and the stem so firmly in position that the fixture and the lamp 40 cannot be shifted accidentally out of position nor will the clamping means loosen up to such an extent as to permit undesirable shifting movement of the lamp.

When the fixture is used on a bedstead 45 of the type indicated at H in Figure 1, a hole is produced in the part H, and the collar C and washer D are slipped over the stem, after which the stem is thrust through the hole, washer g is positioned on the stem,

and nut G is screwed tightly into place, the effect of which is to compress the washer D between the collar C and the bed-element and to so tightly clamp the member A and collar C as to preclude the lamp housing from turning out of its operative position.

To adapt the fixture to a curved rail H' of a metal bedstead, the collar C and washer D are dispensed with. A hole having been provided in the bedrail as shown in Figure 2, the stem B is thrust through it for the curved face a of the member A to have contact directly with the bedrail, and thereupon the washer g and nut G are applied to the stem for drawing the curved face a of said member A into such tight contact with the bedrail that the lamp housing cannot be turned accidentally out of the desired position.

It is apparent that the fixture is applied easily and quickly to any kind of bedstead, or other object, and that it is held securely in position.

Having thus fully described the invention, what I claim as new and desire to secure by Letters Patent is:

A lamp-fixture adapted for use on articles of furniture comprising a head one face of which is curved in conformity with the contour of the surface of the article with which said curved face is adapted to contact, a single stem in permanently fixed relation to said head, said stem passing through said curved face only of the head and protruding for a substantial distance beyond said head to afford means for the attachment of said fixture, a perforated collar fitted loosely and removably on the stem, one face of said collar being curved for snug contact with the curved face of the head and the other side of said collar being a plane surface, and means co-operating with the stem for clamping the collar and the head in fixed non-rotative relation to each other and to the article of furniture.

In testimony whereof I have hereto signed my name this 17th day of February, 1921.

LOUIS ROTH.
